UNITED STATES PATENT OFFICE.

JOHN W. PRICE AND RICHARD M. LEAKE, OF LARAMIE, WYOMING.

PUMP.

Application filed January 20, 1926. Serial No. 32,534.

This invention relates in general to pumps, and more particularly to a pump especially adapted for use in elevating water by means of compressed air.

5 The object of the invention is to provide a pump or water elevator of this character which is highly efficient in that it pumps or elevates a relatively great amount of water with a maximum consumption of power, 10 which is smooth and balanced in its operation and which is of simple and durable construction, reliable in operation and easy and comparatively inexpensive to manufacture.

The present invention consists in a pump 15 or water elevator which includes a plurality of tanks submerged in the water to be pumped or elevated and equipped with check valve controlled inlets and with discharge lines leading from the lower portions of the 20 interior of the tanks. Between the tanks a connection is provided which has its ends communicating with the tanks below the maximum water level in the tanks. An air line leads to the connection and between the point 25 of communication with the air line and the points of communication with the tanks the connection has valve seats with which a shiftable valve loosely mounted in the connection is alternately co-operable under the 30 influence of water flowing from one tank to the other. With this arrangement the water is exhausted from one tank and then from the other and while the water is being exhausted from one tank the other tank is being re-filled. In order to prevent resistance 35 developing to the filling of the tanks venting means are provided in the tanks and preferably are controlled by valves operable from the shiftable valve in the connection so that 40 the action of the main elements of the pump and of the venting means is co-ordinated.

Other objects and advantages reside in certain novel features of the construction, arrangement and combination of parts which 45 will be hereinafter more fully described and particularly pointed out in the appended claims, reference being had to the accompanying drawings forming a part of this specification, and in which:

50 Figure 1 is a view partly in section and partly in elevation showing an embodiment of the invention.

Figure 2 is a fragmentary detail view, 55 partly in section and partly in elevation showing the connection between the tanks and the main ball valve operating therein,

Figure 3 is a similar view of one of the venting valves used to permit filling of the tanks, and

Figure 4 is a similar view showing one of the check valve controlled inlets and a portion of the associated strainer.

Referring to the drawings the numerals 1 and 2 designate a pair of tanks which are located down in the ground and which are 65 submerged in the water to be elevated. Except as hereinafter stated the tanks 1 and 2 are entirely water tight.

The tanks 1 and 2 have water inlets 3 and 4 which are controlled by check valves 5 and 6 to prevent back flow or discharge of water through the inlets. The water is supplied to the check valves through a strainer 7 which may be located between the check valves so as to serve both.

Discharge lines 8 and 9 lead from the tanks 1 and 2, respectively, and each discharge line communicates with the lower portion of its tank, communication in the present instance being afforded through openings or perforations 8^a and 9^a, respectively. Check valves C are incorporated in the discharge lines and above the check valves the discharge lines 8 and 9 merge into a main discharge line D.

A connection, designated generally at 10, is provided between the tanks at a point well below the maximum water level in the tanks. This connection is preferably made up of oppositely inclined sections 10^a and 10^b suitably coupled together and suitably connected to the tanks. As shown in the drawing the tanks 1 and 2 have openings 11 and 12 and the ends of the connection 10 have openings 13 and 14 which register with the openings 11 and 12, respectively.

An air line, designated generally at 15, leads into an intermediate or central portion of the connection 10 and through the air line 15 where pressure or other suitable fluid pressure forms from a tank T or any other suitable source of pressure.

Between the point of communication of the air line 15 with the connection 10 and the openings 13 and 14 (which are the points of communication between the ends of the connection and the tank) valve seats 18 and 19 are provided. A ball valve 20 is loosely or shiftably mounted in the connection 10 and is automatically co-operable with the valve seats 18 and 19.

Venting means are provided for the tanks

and include short pipes 21 and 22 communicating with the upper ends of the tanks 1 and 2 respectively and with compartments 23 and 24 in valve casings 25 and 26, respectively. The compartments 23 and 24 are defined by means of their respective valve casings 25 and 26 and ported partitions 27 and 28, respectively. The partitions 27 and 28 also define compartments 29 and 30 in the valve casings 25 and 26, respectively. The compartments 29 and 30 communicate with a transverse connecting pipe 31 which in turn communicates with a main vent pipe 32. Around the ports of the partitions 27 and 28 valve seats are formed and spring seated valves 33 and 34 co-act with the seats of the ports of the partitions 27 and 28, respectively. The valves 33 and 34 have elongated valve stems 35 and 36 which are suitably fitted in guides provided therefor in valve stem casings 37 and 38, the casings 37 and 38 extending between the valve casings 25 and 26 and the connection 10.

25 The main vent pipe 32 extends downwardly below its connection with the pipe 31 and connects with a tubular valve casing 40 extending between the tanks 1 and 2 adjacent the lower ends. The ends of the casing 40 have ports 41 and 42 around which valve seats are formed and with these valve seats conical valves 43 and 44 co-act. A spring 45 connects the valves 42 and 43 and yieldably hold them against the seats with which they co-act. Flexible elements 46 and 47, such as wires, chains, or the like, are connected to the valves 43 and 44 and to the tanks 1 and 2, respectively, and these flexible elements are positioned to be engaged and depressed by the floats 48 and 49 slidably mounted on guides 50 and 51 in the tanks 1 and 2, respectively.

45 In starting the apparatus, assuming both tanks are full as they usually would be, due to the submersion of the tanks in the water, compressed air is supplied to the air line 15 and will displace the valve 20 to one end or the other of the connection 10, depending upon the position of the valve 20 in the connection. Assuming the valve 20 is displaced to the left as viewed in Figure 1 of the drawing, it is engaged with the seat 18 and this causes the air under pressure to flow through the openings 14 and 12 into the tank 2 wherein the air displaces the water in the tank. At this time the venting valve 34 is closed by its spring. The venting valve 33 is opened by the engagement of the ball 20 with the lower end of its stem 35 but in starting up the pump the position of the valve 33 is immaterial. After the water has been displaced from the tank 2 to such an extent as to carry its level down near the bottom of the tank, the float 49 co-acts with the flexible element 47 to open valve 44 and

the compressed air exhausts through the valve casing 40, the pressure in the tank 2 is materially reduced. At this time the tank 1 is full of water and under the assumed phase of the operation, the head of water in the tank 1 above the connection 10 is effective to displace the valve 20 in the connection 10 and cause the same to travel over to and engage the seat 19 because of the reduced pressure in the tank 2. This shuts off communication between the connection 10 and the tank 2 and establishes communication between the connection 10 and the tank 1. The compressed air now flows into the tank 1 and displaces the water therein through the discharge line 8. When the ball 20 is engaged with the seat 19 it displaces the valve stem 36 upwardly and thereby causes the valve 34 to disengage its seat for the purpose of venting the tank 2 and consequently permitting the water in which the tanks are submerged to flow into the tank 2 while the tank 1 is being emptied. As soon as the water level rises in the tank 2 the float 49 will disengage the flexible element 47 and permit the spring 45 to close the valve 44. The tank 2 will be filled before the tank 1 is entirely emptied by virtue of the proper proportioning between the sizes of the inlets 3 and 4 and the sizes of the discharge 9 and the openings 11, 12, 13 and 14. While the tank 1 is being emptied the valve 33 is closed by the spring so as to prevent the compressed air escaping through the vent. After each tank is emptied the head of water in the other tank causes the water to flow from one tank to the other valve 20 resulting in the reversal of the operation. In this way first one and then the other tank is filled and emptied so that a continuous supply of water is automatically had.

We claim:

1. A pump including a pair of tanks, check valve controlled inlets to said tanks, discharge means for the tanks, an air line, a connection communicating with said air line and with both of said tanks at points below the maximum water level in the tanks, a valve member loosely mounted in the connection and shiftable therein under the influence of water flowing from one tank to the other and operable to control the communication of the air lines with the tanks and venting means associated with the tanks.

2. A pump including a plurality of connected tanks, inlet means for the tanks, discharge means for the tanks, a source of fluid under pressure, automatically operable venting means, and means connected with the source of fluid under pressure and with the tanks, said means including a valve operable by the action of the fluid under pressure and by the flow of water from one tank to another for controlling the communica-

tion between the source of fluid under pressure and the tanks.

3. A pump including a pair of submerged tanks, check valve controlled inlets to said tanks, discharge lines leading from the lower portions of the tanks, a connection having its ends communicating with the tanks below the maximum water level in the tanks, an air line leading to the connection, said connection having valve seats between the point of the communication of the air line therewith and the points of communication of the connection with the tanks, a valve loosely mounted in the connection and shiftable therein under the influence of water flowing from one tank to the other, said valve being alternately engaged with the valve seats to control the communication of the air lines and the tanks, and venting means associated with the tanks.

4. A pump including a pair of submerged tanks, check valve controlled inlets to said tanks, discharge lines leading from the lower portions of the tanks, a connection having its ends communicating with the tanks below the maximum water level in the tanks, an air line leading to the connection, said connection having valve seats between the point of the communication of the air line therewith and the points of communication of the connection with the tanks, a valve loosely mounted in the connection and shiftable therein under the influence of water flowing from one tank to the other, said valve being alternately engaged with the valve seats to control the communication of the air lines and the tank, venting means to prevent filling of the tanks, and valves controlling said venting means and operated by the shiftable valve of the connection.

5. A pump including a pair of submerged tanks, check valve controlled inlets to said tanks, discharge lines leading from the lower portions of the tanks, a connection having its ends communicating with the tanks below the maximum water level in the tanks, an air line leading to the connection, said connection having valve seats between the point of the communication of the air line therewith and the points of communication of the connection with the tanks, a ball valve loosely mounted in the connection and shiftable therein under the influence of water flowing from one tank to the other, said valve being alternately engaged with the valve seats to control the communication of the air lines and the tank, venting means to prevent filling of the tanks, and valves controlling said venting means and having stems engaged with the ball valve whereby the venting valves are automatically controlled.

6. A pump including a pair of tanks, check valve controlled inlets to said tanks, discharge means for the tanks, an air line, a

connection communicating with said air line and with both of said tanks at points below the maximum water level in the tanks, a valve member loosely mounted in the connection and shiftable therein under the influence of water flowing from one tank to the other and operable to control the communication of the air lines with the tanks, and automatically operable venting means for reducing the pressure in either tank when the water level therein falls below a predetermined point.

7. A pump including a pair of submerged tanks, check valve controlled inlets to said tanks, discharge lines leading from the lower portions of the tanks, a connection having its ends communicating with the tanks below the maximum water level in the tanks, an air line leading to the connection, said connection having valve seats between the point of communication of the air line therewith and the points of communication of the connection with the tanks, a main valve loosely mounted on the connection and shiftable therein under the influence of water flowing from one tank to the other, said valve being alternately engaged with the valve seats to control the communication of the air lines and the tank, venting means for permitting filling of either tank and for reducing the pressure in either tank when the water level falls below a predetermined point and comprising a main vent pipe, valve controlled connections between the upper ends of the tank and the vent pipes, and valve controlled connections having means co-operable with the main valve whereby the main valve controls the same, a valve casing connecting the vent pipe and the lower ends of the tank, and float-controlled valves for controlling communication between the valve casing and the lower ends of the tank.

8. A pump including a pair of submerged tanks, check valve controlled inlets to said tanks, discharge lines leading from the lower portions of the tanks, a connection made up of oppositely inclined sections and having its ends communicating with the tanks below the maximum water level in the tanks, an air line leading to the connection, said connection having valve seats between the point of the communication of the air line therewith and the points of communication of the connection with the tank, a main valve loosely mounted in the connection and shiftable therein under the influence of water flowing from one tank to the other, said valve being alternately engaged with the valve seats to control the communication of the air lines and the tanks, and venting means associated with the tanks.

9. A pump including a pair of tanks, check valve controlled inlets to said tanks, discharge means for the tanks, an air line, a connection communicating with said air line

and with both of said tanks at points below the maximum water level in the tanks, a valve member loosely mounted in the connection and shiftable therein under the influence of water flowing from one tank to the other and operable to control the communication of the air lines with the tanks, and automatically operable venting means

for reducing the pressure in either tank when the water level therein falls below a ¹⁰ predetermined point including spring closed valves, flexible elements connected to said spring closed valves, and floats co-operable with the flexible elements to open the valves.
